US00D932818S

(12) **United States Design Patent** (10) **Patent No.:** **US D932,818 S**
(45) **Date of Patent:** **** Oct. 12, 2021**

(54) **ADJUSTABLE SHELF**

(71) Applicant: **Dedee R. Dart**, Mapleton, UT (US)

(72) Inventors: **Dedee R. Dart**, Mapleton, UT (US);
Bart Storrs, Highland, UT (US)

(73) Assignee: **Dedee R. Dart**, Mapleton, UT (US)

(**) Term: **15 Years**

(21) Appl. No.: **29/769,926**

(22) Filed: **Feb. 8, 2021**

Related U.S. Application Data

(63) Continuation-in-part of application No. 29/754,701, filed on Oct. 13, 2020, which is a continuation of application No. 29/689,053, filed on Apr. 26, 2019, now Pat. No. Des. 898,489.

(57) **CLAIM**

The ornamental design for the adjustable shelf, as shown and described.

DESCRIPTION

FIG. 1 is a perspective top back view of the adjustable shelf of the present invention in expanded form;

FIG. 2 is a perspective bottom front view of the adjustable shelf of the present invention in expanded form;

FIG. 3 is a back side view of the adjustable shelf of the present invention in expanded form;

FIG. 4 is a front side view of the adjustable shelf of the present invention in expanded form;

FIG. 5 is a right side view of the adjustable shelf of the present invention in expanded form;

FIG. 6 is a left side view of the adjustable shelf of the present invention in expanded form;

FIG. 7 is a top side view of the adjustable shelf of the present invention in expanded form;

FIG. 8 is a bottom side view of the adjustable shelf of the present invention in expanded form;

FIG. 9 is a perspective top back view of the adjustable shelf of the present invention in collapsed form;

FIG. 10 is a perspective bottom front view of the adjustable shelf of the present invention in collapsed form;

FIG. 11 is a back side view of the adjustable shelf of the present invention in collapsed form;

FIG. 12 is a front side view of the adjustable shelf of the present invention in collapsed form;

FIG. 13 is a right side view of the adjustable shelf of the present invention in collapsed form;

FIG. 14 is a left side view of the adjustable shelf of the present invention in collapsed form;

FIG. 15 is a top side view of the adjustable shelf of the present invention in collapsed form; and,

FIG. 16 is a bottom side view of the adjustable shelf of the present invention in collapsed form.

1 Claim, 16 Drawing Sheets
